DESIGN FOR A WATERTIGHT BAG

Hans Georg Morner, New York, N. Y.

Application April 23, 1943, Serial No. 110,024

Term of patent 14 years

To all whom it may concern:

Be it known that I, Hans Georg Morner, a subject of the King of Sweden, residing in the city, county, and State of New York, have invented a new, original, and ornamental Design for a Watertight Bag, of which the following is a specification, reference being had to the accompanying drawing, forming a part thereof.

Figure 1 is a perspective view of a watertight bag showing my new design; and

Figure 2 is a similar view from the other side with the upper flaps of the bag laid back.

I claim:

The ornamental design for a watertight bag, as shown.

HANS G. MORNER.
